CLOSING DEVICE FOR GRIPPING A STRAND OF HAIR IN
HEATING TUBES FOR HEATING STRANDS OF HAIR

UNITED STATES PATENT OFFICE

GUILLAUME DUCART, OF PARIS, FRANCE

CLOSING DEVICE FOR GRIPPING A STRAND OF HAIR IN HEATING TUBES FOR HEATING STRANDS OF HAIR

Application filed October 13, 1930, Serial No. 488,486, and in France October 24, 1929.

My invention relates to the tubes or heaters employed in the treatment of strands of hair by heat and in particular in those for obtaining a so-called permanent wave, the strands of hair being generally impregnated with a suitable solution before being inserted in heating tubes in which this solution is evaporated.

The object of the invention is to provide a closing device for gripping the strand of hair, for use with these heating tubes, this device being mounted at the end of the heating tubes and presenting numerous advantages. In particular it presents the following advantages: It performs the double function of a closing device for gripping the strand of hair and a very efficient means for protecting the head from the heat of the heating tube; it is of very small size and of little weight; it provides an absolutely fluid tight closure and it can be combined with independent closing means.

On account of the two-fold function they perform, that of acting as closing means and of protecting the head, the closing devices according to the invention, which are simple in construction and extremely easy to position, provide a simplification with respect to the existing devices employed, which comprise on the one hand the closing device for the heating tube of more or less complicated construction, most frequently mounted like the hinged stoppers of beer bottles, and on the other hand the protecting member, which is generally in the form of a washer made of flannel, leather, etc. This simplification which is obtained according to the invention in the construction of the apparatus, provides a still greater simplification in the positioning and removal, since the protecting washers are dispensed with, whereby the duration of the operations is considerably reduced.

On the other hand, on account of the arrangement of fins provided beneath the base of the closing device, the area of contact between the closing device and the head is reduced and air is allowed to flow between the closing device and the scalp. Moreover, the combination in the closing devices according

to the invention of closing devices proper and devices for protecting the scalp in one and the same device, has the effect of reducing the space occupied by the arrangement formed by these members.

On account of this feature the height is reduced to a minimum and it becomes possible to commence the waving of the strands of hair almost on the surface of the scalp and a better wave is consequently obtained. Further, the width and the weight are also reduced, so that the whole of the heating tubes required for waving the whole of the head can be placed on a customer's head, without inconveniencing the latter, that is to say approximately forty tubes each containing a strand of hair, thus reducing considerably the duration of the work in view of the fact that at the present time it is not possible, with the apparatus employed, to put more than twenty to twenty-five tubes approximately in position at the same time, thus making it necessary to carry out two successive operations for waving a complete head.

On account of the absolute fluidtight closure obtained with the closing devices for gripping the strands of hair according to the invention, all risk of any leakage of vapours from the heating tubes on to the customer's head is avoided.

Finally, the fact that the means for closing the closing devices can be removed from the body of the said closing devices facilitates cleaning the latter and permits the same gripping means to be used for a new closing device when the one to which they were attached is out of use.

These advantages and others not mentioned will moreover appear more clearly from the following description of a closing device for gripping a strand of hair constructed according to the invention and illustrated diagrammatically by way of constructional embodiment in the accompanying drawings to which reference will be made.

In these drawings:

Figure 1 is a front elevation of the closing device for gripping the strand of hair, assumed to have been secured on a strand of

hair at the root and provided with a clamping yoke.

5 Figure 2 is a vertical diametral section taken along the plane B B, of the slot in the closing device, in which slot the strand of hair is gripped.

Figure 3 is a plan of Figure 1, viewed from above.

10 Figure 4 is a plan view of the under face of the closing device, which is assumed to have been turned over in order to show the base provided with the protecting fins.

15 Figure 5 is a diametral section taken along the line A A, of the closing device provided with the clamping yoke.

Figure 6 is a front elevation of the clamping yoke shown alone, and

20 Figure 7 is a plan of the yoke viewed from below.

25 In these figures, 1 is a closing device formed by a block of rubber hollowed out at its upper part at 2, so as to be capable of receiving the base of a heating tube such as 3 in which is situated the strand of hair 4 wound upon a curler 5. The recess 2 in the closing device 1 preferably comprises at its base an annular groove 6 in which is engaged the lower rolled edge 7 of the tube 3, thus providing a perfect engagement of the closing device over the tube.

30 At the lower part the rubber closing device 1 comprises a series of projections, ribs or fins 8 moulded on its base and adapted to reduce the surface of contact of the closing device with the head, while permitting air to circulate between the scalp and the closing device. According to the form of construction which seems preferable, the fins 8 have the form of wedges rising on the base 1^a of the closing device, from the periphery towards the centre. This arrangement permits an efficient circulation of air and reduces the surface of contact between the closing device and the head to a minimum, thus practically annuling the effects of radiation of the heating body towards the scalp.

35 The closing device 1, made of rubber, is split at 9, after moulding, over the whole of its height along a diametral plane; the slot 9 does not however extend over the whole diameter, as shown in Figures 2, 3 and 4 so as to allow the part which is not split to form a hinge.

40 In order to produce the action of the lips of the slot 9 which is necessary in order to make the closing device absolutely fluid tight, between which lips the strand of hair 4 passes and is gripped, clamping means independent from the closing device are provided.

45 50 55 60 65 In the example illustrated these means consist in a metal yoke (Figures 6 and 7) the arms 10 and 11 of which are pivoted at 12 and each terminate in an inclined raised portion 10^a and 11^a respectively. Upon the inclined raised portion 10^a a closing bar 13

is mounted on a hinge at 15 in an inclined plane in which bar is formed a longitudinal slot 14 in which the inclined raised portion 11^a of the arm 11 of the pivoted yoke engages in the closed position. In the end of the bar 70 13 is provided an internal thread receiving a clamping screw 16 the point of which acts on the raised portion 11^a engaged in the slot 14.

When the raised portion 11^a is engaged 75 in the slot 14, as shown in the drawing, the arm 11 of the yoke can be made to approach the arm 10 by operating the screw 16 acting upon the raised portion 11^a which is adapted to slide in the slot 14, thus increasing the 80 clamping action of the member adapted to be interposed between the two arms.

On the contrary, in order to remove this clamping action, it is sufficient, after having unscrewed the screw 16, to make the bar 13 85 swing upwards about the pivot 15, thus disengaging the arm 11 which can then be pivoted about the pivot 12 (as shown in dotted lines in Figure 7.)

The closing device is constructed in such 90 a way that the body itself of the closing device is separated from the base 1^a by a deep groove and is only connected to the base by a diametral block 1^b (Figure 5) of rectangular or trapezoidal shape, over which the 95 yoke 10, 11 engages, the arms of the latter exerting their pressure on the walls of the said block which is, moreover, shaped in such a way as to permit the lodgment of the pivot ends of the arms 10 and 11, the body of the 100 closing device being moreover recessed at 17 in order to permit this lodgment.

In order to provide a more efficient gripping action by making it bear over the whole 105 of the height of the slot 9 dividing the closing device, the arms 10 and 11 of the yoke are provided with upper extensions or frames 10^b and 11^b engaging the external surface of the closing device 1 and gripping the 110 projecting angles 1^c of the closing device.

In addition, the base 1^a of the closing device is extended by a lug 1^d upon which rests the bar 13 of the clamping yoke.

With the devices thus constructed, their 115 method of use is easily understood. The strand of hair 4 being assumed to be wound on a curler 5, it is inserted as near as possible to the root in the slot 9 of the closing device which, on account of its elasticity, exerts a flat grip on the strand of hair inserted in the slot.

An open yoke is then taken which is inserted in the space existing between the body itself of the closing device and its base 1^a, the yoke being arranged in such a way that its arms 10 and 11 are situated on either side of 125 the walls of the solid part 1^b and the joint 12 situated in the axis of the slot 9 on the undivided side.

The yoke is then closed as described above and an absolutely fluid tight joint is obtained. 130

The heating tube 13 is next placed round the curler 5 and is inserted in the upper recess 2 of the closing device with the edge 7 of the said tube penetrating into the groove 6.

- 5 It is clearly understood that without going outside the scope of the invention modifications and improvements of details may be made, and similarly the use of equivalent means may be imagined.
- 10 It is also clearly understood that this type of closing device may be employed for all tubes in which strands of hair are treated, other than by heat.

What I claim is:

- 15 1. A closing device for gripping a strand of hair, adapted to be fitted at the end of tubes in which the strands of hair are treated by heat or otherwise, in particular for obtaining so-called permanent waves, the said closing device being characterized by the feature that it is formed by a rubber block split diametrically over the whole of its height while leaving a solid part forming a hinge, the said rubber block being shaped so as to comprise a recessed part receiving the end of the heating tube, seatings for receiving the action of a clamping member and a base provided with projections, ribs or fins reducing the contact surface between the closing device and the head and permitting air to circulate between the closing device and the scalp.
- 20 2. A closing device for gripping a strand of hair as claimed in claim 1, wherein the fins provided upon the base of the closing device have the form of wedges rising on the base from the periphery to the centre.
- 25 3. A closing device for gripping a strand of hair as claimed in claim 1, wherein the clamping member is removable and is formed by a yoke the arms of which exert a gripping action over the outer walls of a small diameter part connecting the body itself of the closing device with the base, the said arms preferably further comprising frames engaging the outer surface of the said closing device and adapted to grip projecting angles on the closing device, the yoke being closed by means of a bar hinged upon one of the arms and comprising a slot in which the end 30 of the outer arm can be made to move by means of a clamping screw.
- 35 40 45 50

In testimony whereof I affix my signature.
GUILLAUME DUCART.
